UNITED STATES PATENT OFFICE.

PAUL A. NEWMAN, OF GERMANTOWN, PENNSYLVANIA, ASSIGNOR TO WESTERN ELECTRIC COMPANY, INCORPORATED, OF NEW YORK, N. Y., A CORPORATION OF NEW YORK.

INTERRUPTER.

Application filed December 29, 1923. Serial No. 683,300.

To all whom it may concern:

Be it known that I, PAUL A. NEWMAN, a citizen of the United States of America, residing at Germantown, in the county of 5 Philadelphia and State of Pennsylvania, have invented certain new and useful Improvements in Interrupters, of which the following is a full, clear, concise, and exact description.

10 This invention relates to commutators and more particularly to improvements in a construction of commutators to eliminate sparking of the brushes thereof.

This invention may be embodied in the 15 construction of slow speed commutator type interrupters of ringing machines used in telephone systems where the slow speed and changing current conditions may ordinarily cause the segments of the interrupter rings 20 to burn.

It is an object of this invention to construct an interrupter of the above or any other type so as to prevent sparking and thus save the segments from burning at the 25 points where the make and break occurs.

Another object is the provision of an interrupter in which the segments are embedded in and held in place by a molded insulating material and in which this insulating material may be brought flush with the outer edges and surfaces of the segments without danger of overheating which would ordinarily have an injurious effect on the interrupter such as carbonization of the insulation and burning of the contact surfaces.

To attain these objects in accordance with one feature of this invention, a series of auxiliary segments are provided on both 40 sides of each live segment and each group of auxiliary segments is connected to each other and to the corresponding live segments by means of resistance elements so that the circuit between the brushes and a 45 live segment is made or broken in steps to increase or reduce the voltage and current in suitable values.

Another feature is the arrangement whereby the resistance elements are molded into 50 and enclosed by the insulating material and suitably arranged around the hub of the interrupter as well as connected to their respective segments before they are embedded

in the material to produce an entirely self-contained interrupter of this type. 55

A particular embodiment of this invention as applied to a commutator type ringing machine interrupter is illustrated in the accompanying drawing in which Fig. 1 is a front view of such an interrupter with a portion broken away to show the resistance units and the manner in which they are secured to the segments. Fig. 2 is a side view of the invention with a portion in cross section along the lines 2—2 of Fig. 1. 60 65

Referring now to the drawing, the interrupter comprises circumferentially arranged comparatively wide live segments 1 and 2 with a plurality of comparatively narrow auxiliary segments 3 arranged on both 70 sides of each live segment, and resistance coils 4 suitably arranged around the hub 5 and connected by means of conductors 6 to the auxiliary segments 3 and the live segments 1 and 2 as shown. Flush with these 75 segments on one side thereof is a solid contact ring 7 and all of these parts, that is, segments, resistances and the ring are embedded and held together by suitable insulating material preferably molded around 80 the parts. The ring 7 is connected to the live segments 1 and 2 by means of conductors 8 and the brushes 9 and 10 serve to complete connections between brush 9, conductors 8, live segments 1 or 2, resistance 85 units 4, the auxiliary segments 3 and brush 10. It is evident then that circuits so completed will eliminate sparking at the brushes as when, for example, the interrupter is rotated in the direction shown by the arrow 90 in Fig. 1, the brush 10 comes first in contact with an auxiliary segment 3 and a circuit will thereby be completed through all the resistance units 4 to the brush 9 and as the interrupter continues to rotate, one 95 of these resistance units after another will be eliminated in the succeeding steps until the brush 10 is in contact with the live segment 1, when a direct circuit extending through the brush 10, segment 1, ring 7 100 and brush 9 is completed. In a similar manner, when the brush 10 leaves the live segment 1, it will proceed to gradually open the circuit by interposing a series of resistance units 4, one for each auxiliary seg- 105

ment passed until the circuit is finally com-

pletely broken when it leaves the last auxiliary circuit 3. The current is therefore gradually stepped up from zero to a maximum value and gradually stepped down 5 from this maximum value to zero, each time the brush 10 makes and breaks connection with a live segment. While the exact size or width of the brush 10 is not of material importance, its width should not be less than 10 the distance between two adjacent auxiliary segments or the distance between an auxiliary segment and the adjacent live segment so as to bridge two adjacent segments when passing from one to another. 15 As the invention thus provides means for eliminating the sparking at the edges of the contact surfaces and brushes the insulation, which may be of any suitable and similar material throughout the whole mass, may 20 be brought flush with the entire contact surfaces of the segments without danger of overheating the edges of the insulating material or burning of the edges of the segment. If, therefore, the insulating material 25 is such as to wear at the same or approximately the same rate as the contact segments, a smooth and even surface will be secured that is highly effective for use in interrupters of this type where the current 30 conditions and the speed of the interrupter are apt to vary to a large degree. It is also of advantage to have the width of the contact surfaces of the auxiliary segments comparatively narrow as compared with the 35 width of the live segments. It should be noticed that the contact segments are suitably shaped on the inner edges or surfaces so as to be gripped by the molded material and held securely in place thereby and not 40 become loose under any conditions of service. The particular contour of these inner surfaces of the segments is of minor importance but may take the form of longitudinal grooves such as 11 shown in the drawing 45 and any other configurations most suitable for different types. The size and position of the contact ring 7 in relation to the contact segments may also be changed to suit various requirements. 50 What is claimed is:

1. An interrupter comprising a plurality of metallic main contact segments, a solid metal contact ring adjacent thereto and connecting with said segments, a series of comparatively narrow metal contact segments adjacent the ends of each main segment, resistance units connecting the auxiliary segments with each other and with the corresponding main segment, and a body of insulating material holding said segments and ring in place. 55
2. In an interrupter, the combination of a plurality of main contact segments, a series of auxiliary segments at each end of each 60 main segment, and means for preventing

sparking comprising a resistance unit interposed between each two adjacent auxiliary segments and between the corresponding main segment and the auxiliary segments at each end thereof. 70

3. In an interrupter, the combination of a plurality of main contact segments, a group of auxiliary segments adjacent each end of each main segment, resistance elements connecting each two auxiliary segments in a group and connecting the auxiliary segments nearest the ends of each main segment with said main segment, and a body of insulating material for holding said segments and resistance units in place. 75

4. In an interrupter, the combination of conducting segments, resistance units connecting them together and a body of insulating material holding said segments and resistance units together. 80

5. An interrupter composed of conducting segments, resistance units connecting said segments together and a body of insulating material in which said segments and resistance units are entirely enclosed except 90 the contact surfaces of the segments. 90

6. In combination in an interrupter, a plurality of main conducting segments, a plurality of auxiliary conducting segments adjacent each end of said main segments, resistance elements connecting each two adjacent auxiliary segments and connecting the auxiliary segments adjacent each main segment to said main segment, a hub and an insulating body connecting all of said 100 parts together. 95

7. An interrupter comprising a plurality of main segments circumferentially arranged in relation to each other and having irregular internal surfaces, a plurality of auxiliary segments arranged circumferentially adjacent to each end of each main segment and having similar irregular internal surfaces, resistance elements interposed between each pair of auxiliary segments and between the auxiliary segments and the corresponding main segments, and an insulating body molded to enclose the resistance elements therein and to key said segments together by being interposed into 110 the openings formed by their irregular internal surfaces. 115

8. A circuit interrupter comprising a series of segments having contact surfaces of varying widths and arranged circumferentially in relation to each other, resistances connected between said segments, the segments being so arranged that a segment having a comparatively wide contact surface is connected by resistance units with a group of segments on either side thereof having comparatively narrow contact surfaces, and an insulating body enclosing all of said segments and resistance units except the contact surfaces of the segments. 120 125 130

9. A circuit interrupter comprising a series of segments having contact surfaces of varying widths arranged circumferentially in relation to each other, resistances connected between said segments, these segments being so arranged that a segment having a comparatively wide contact surface is connected by resistance units with a group of segments on either side thereof having comparatively narrow contact surfaces, and a complete commutator ring having its contact surface adjacent the contact surfaces of said segments and connected to the segments having wide contact surfaces and an insulating body enclosing all of said elements except the contact surfaces of said elements.

10. A circuit interrupter comprising a series of segments having contact surfaces of varying widths arranged circumferentially in relation to each other, resistances connected between said segments, the segments being so arranged that a segment having a comparatively wide contact surface is connected by resistance units with a group of segments on either side thereof having comparatively narrow contact surfaces, and a complete commutator ring having its contact surface adjacent the contact surfaces of said segments and connected to the segments having a wide contact surface, and insulating body enclosing all of said contacts and resistance units except the contact surfaces of said element and brushes, one for the contact surfaces of the segments and the other for the contact surface of the commutator ring.

11. A circuit interrupter comprising a series of segments having contact surfaces of varying widths arranged circumferentially in relation to each other, resistances connected between said segments, the segments being so arranged that a segment having a comparatively wide contact surface is connected by resistance units with a group of segments on either side thereof having comparatively narrow contact surfaces, and a complete ring having its contact surface adjacent the contact surfaces of said segments and connected to the segments having a wide contact surface, an insulating body enclosing the resistances and all of said contact elements except the contact surfaces thereof, one brush for the contact surfaces

of the segments and having a contact surface wider than the distance between the contact surfaces of two adjacent segments and another brush for the contact surface of the ring.

12. A circuit interrupter comprising a series of segments having contact surfaces of varying widths arranged circumferentially in relation to each other, resistances connected between said segments and the segments being so arranged that a segment having a comparatively wide contact surface is connected by resistance units with a group of segments on either side thereof having comparatively narrow contact surfaces, and an insulating body enclosing all of said segments and resistance units except to contact surfaces of the segments, and a brush having a contact surface wider than the distance between the contact surfaces of two adjacent commutator segments.

13. A commutator comprising groups of contact segments, each group comprising one comparatively wide segment and a number of comparatively narrow segments on either side thereof, the narrow segments being of the same width and spaced equi-distance apart from each other and from the corresponding wide segment, resistances inserted between the segments in each group and an insulating body enclosing the segments and resistances entirely except for the contact surfaces of the segments.

14. A commutator comprising groups of contact segments circumferentially arranged, each group comprising one wide segment and a number of comparatively narrow segments of equal width on either side thereof, and spaced an equal distance apart from each other and from the wide segment, a brush adapted to connect with said segments wider than the narrow segments and wide enough to bridge the distance between two segments in a group, resistances inserted between the segments in each group and a body of insulating material in which the resistances are entirely enclosed and serving to hold the segments in place.

In witness whereof, I hereunto subscribe my name this 27th day of December A. D., 1923.

PAUL A. NEWMAN.
